UNITED STATES PATENT OFFICE.

JAMES CULTON, OF DENVER, COLORADO.

RAILWAY-TRACK TRIP.

1,241,712.

Specification of Letters Patent.

Patented Oct. 2, 1917.

Application filed July 20, 1915. Serial No. 40,899.

To all whom it may concern:

Be it known that I, JAMES CULTON, a citizen of the United States, residing at Denver, in the county of Denver and State of Colorado, have invented certain new and useful Improvements in Railway-Track Trips, of which the following is a specification.

This invention relates to track appliances 10 of the type used in systems for the automatic control of the movement of power driven vehicles along a railroad, such as is described in my application for patent Serial No. 833,391, filed April 21, 1914.

15 The present invention relates more particularly to devices of the character shown and described in my application for patent Serial No. 795,046 filed October 14, 1913, and its primary object resides in providing 20 in combination with the yieldingly supported trip rail of a track appliance of the type above mentioned, a spring-operated blocking mechanism the positions of which are controlled by an electro-magnetic device 25 which is connected in the normally closed line circuit of a railway signaling system.

The controlling device is connected in the circuit with relation to a semaphore forming part of the signaling system, so that 30 when the circuit is opened, the blocking mechanism operates to place the track appliance in operative condition, irrespective of the condition or operation of the signaling instrument.

35 Another object of my invention resides in providing in operative connection with the track appliance, a detonating signaling apparatus which operates each time the track appliance in its effective condition 40 causes the operation of a movement-controlling mechanism on a passing vehicle, and still another object resides in improvements in the mechanical construction of the track appliance, including protective means 45 for insulating the operating mechanism of the same from dirt, dust and moisture.

In the accompanying drawings in the various views of which like parts are similarly designated,

50 Figure 1 is a horizontal section through the track appliance on a plane designated by the line 1-1, Fig. 2,

Fig. 2, a vertical section taken along the line 2-2, Fig. 1;

Fig. 3, a transverse section along the line 55 3-3, Fig. 1 showing the appliance operatively connected with the electro-magnetic device which controls the operation of its blocking mechanism;

Fig. 4, a section taken along the line 4-4, 60 Fig. 1,

Fig. 5, a fragmentary elevation of the track appliance showing the detonating signaling apparatus connected therewith,

Fig. 6, a fragmentary plan view of the 65 apparatus shown in Fig. 5,

Fig. 7, a section taken along the line 7-7, Fig. 1,

Fig. 8, a detail view of the ratchet movement included in the detonator signaling 70 apparatus shown in Fig. 5,

Fig. 9, an enlarged detail view of the cam included in the mechanism illustrated in Fig. 8,

Fig. 10, a diagrammatic view of a system 75 of track appliances and electrical connections in association with a railroad and the line circuit of a track signaling system, and

Fig. 11, a fragmentary end view of a modified construction of the trip rail of the 80 track appliance and the contact wheel of the operating medium of a locomotive-carried, movement-controlling mechanism riding along the tread thereof.

Referring first to Figs. 1 to 4 of the drawings, the track appliance comprises a box-shaped, hollow base 2 covered by a hollow trip-rail 3 which is vertically yieldingly supported upon the bottom surface of the same through the intermediary of coiled 90 springs 4.

The base is secured upon a foundation 21 of concrete or other suitable material by means of anchor bolts 22 projecting through openings in a flange 23 and provided with 95 nuts 24.

The rail has in its circumferential wall 7, a narrow recess 5 to receive the upper portion of the corresponding wall 6 of the base, and its upper surface is curved to provide a convex tread 9.

A strip 8 of steel or other resilient material fastened along the lower edges of the movable rail frictionally engages the outer

faces of the upright wall of the base to protect the operating mechanism within the base against dirt and moisture.

When the rail is free to move downwardly by compression of the springs upon which it is supported, the track appliance is in its normal ineffective or inoperative condition and the operating medium 74 of a movement-controlling mechanism on a passing vehicle when riding along the curved tread of the rail, will merely depress the latter without affecting the mechanism with which it is actuatedly associated.

To produce this result the operating medium 74 is yieldingly held against upward movement by a spring whose pressure resisting strength slightly exceeds that of the combined springs upon which the rail is supported.

In the construction shown in Figs. 3, 4 and 7 the tread of the rail 3 is flat to be engaged by a rotary wheel 75 at the lower end of the operating medium hereinbefore referred to, which is peripherally sharpened to provide a cutting edge adapted to penetrate snow, mud or other obstructive matter deposited on the rail. The same result may be obtained, however, by making the tread of the rail a longitudinally extending sharp ridge as shown at 76 in the modified construction illustrated in Fig. 11, in which case the wheel 75 of the operating medium is peripherally flat.

To place the track appliance in an operative condition, its rail is blocked against downward movement whereby to compel the operating medium of the automatic-movement controlling mechanism on a passing vehicle to ascend along its tread to the apex thereof and thereby effect a determinate movement of the said mechanism.

The blocking mechanism consists of four blocks 10 which are normally supported upon rests 12 on the inside of the base in register with alined slots 13 and 14 in the upright wall 6 of the base, and the members of the wall 7 of the rail between which the latter is disposed.

The blocks which are arranged in pairs at opposite sides of the longitudinal axis of the base, are held in their normal position in which they are retracted from the slots 13 and 14, by an electro-magnetic device hereinafter to be described.

To block the downward movement of the rail, the stops 10 are projected into the slots in the base and the rail by the expansion of four springs 15 after the controlling device which normally holds them in their retracted position, has been actuated to release the same.

The stops comprised in one of the two pairs are secured at the end of a bar 16 which at a central point has a laterally projecting arm 17 for its pivotal connection with the

ends of two normally alined levers 18 which are fulcrumed upon the base 19 and which at the ends of their opposite arms are pivotally connected with the stops comprised in the other pair.

The springs which as stated hereinbefore are provided to project the stops into the slots of the rail for the purpose of blocking the downward movement of the same, are disposed between standards 20 on the base.

The springs are coiled around rods 25 which extend from the standards loosely through openings in the bar 16 and the levers 18, and they are compressed ready for action while the blocks are held in their normal retracted position as shown in Fig. 1 of the drawings.

The electro-magnetic device which controls the position of the stops, consists as best shown in Fig. 3 of the drawings, of a solenoid 26 the core 27 of which is by means of an integral angular bar 28 connected with the arm 17 of the bar 16.

The core carries at its opposite end a wedge-shaped spreader 78 of nonconductive material which normally separates two resilient contact blades 29 to open a circuit in which the latter are connected.

A device for locking the core in two determinate positions consists of an electromagnet 30 the armature 31 of which is operatively connected with two dogs 32 and 33 adapted to respectively enter notches 34 and 35 formed in the core at different distances from its adjacent extremity.

The dog 32 is rigidly connected with the armature and the other dog is secured at the end of a lever 36 fulcrumed as at 37, which at its opposite end is attached to the first-mentioned dog.

A spring 38 applied between the cooperatively connected dogs and a relatively fixed part, serves to reverse their position when the magnet 30 is deenergized.

When the track appliance is in its normal inoperative condition, the solenoid 26 is inactive and the dog 32 is by the attractive force of the normally active magnet 30, held in a position in which it occupies the notch 34 of the solenoid core.

The spreader 78 at the end of the core separates under these conditions, the two contact blades 29 and thereby opens the circuit in which they are connected, and the bar 16 and the levers 18 are held in their normal position by the bar 28 which operatively connects them with the opposite end of the solenoid core.

The dog 33 is separated from the core until after the magnet is deenergized, the spring 38 withdraws the dog 32 from its notch and at the same time moves the other dog about the fulcrum of its lever to frictionally engage the core.

The coöperative devices which control the

blocking mechanism are inclosed in a water-tight casing 39 which is embedded in the ground in connection with the base of the track appliance.

5 The latter is to this end provided with a sump 40 having a laterally extending box 41 which by means of a drawnut 42 is connected with a similar box 43 at the end of the casing 39.

10 The angular bar 28 extends through aligned bores in the two boxes which if so desired may be provided with packing rings for the usual purpose.

15 The solenoid 26 and the magnet 30 are connected in independent circuits the flow of current through which is controlled by a relay 46 connected in the normally closed line circuit of a railway track signaling system.

20 The last-mentioned circuit which as shown in Fig. 10, usually includes the rails of a railroad track, is designated in Fig. 3 by the lines 44 and 45 and the conductors which connect the coil of the relay in the circuit, by the lines 47 and 48.

25 The solenoid circuit includes commencing at the source of electricity 49, a conductor 50, the windings of the solenoid coil, a conductor 51, the two contact blades 29, a pair of insulated contact pieces 52 which normally are engaged by the armature of the relay, and a conductor 53 which connects with the opposite pole of the source.

30 The circuit of the electro-magnet 30 includes commencing at a source of electricity 54 of less electro-motive force than the source of the solenoid circuit, a conductor 55, the windings of the magnet coil, a conductor 56, a pair of insulated contact pieces 58 which are normally engaged by the armature of the relay, and a conductor 59 which connects with the opposite pole of the source 54.

35 When the line circuit is in its normal, closed condition and the semaphores of the signaling system are set at "safety," the relay 46 is energized thereby closing the magnet and solenoid-circuits by the engagement of its armature with the contact pieces 52 and 58.

40 50 The dog 32 occupying the notch 34 of the solenoid core is as hereinbefore explained, held in place against the action of its spring 38 by the attractive force of the magnet and the core is in consequence locked in the position in which it holds the stops of the blocking mechanism in their retracted position against the action of the springs 15, and in which the spreader 78 is positioned between the contact blades 29 to open the solenoid circuit at that point.

45 55 Now, when for the purpose of reversing the semaphores to a position indicative of danger, the line circuit is opened, or in case it is accidentally broken as for example by a break in the rail which constitutes one of its

conductors, the relay is deenergized thereby opening the solenoid- and magnet-circuits by separating its armature from the contact pieces 52 and 58. The consequent demagnetization of the electro-magnet 30 compels 70 the spring 38 to move the lever 36 about its fulcrum whereby the dog 32 is withdrawn from the notch 34 in the solenoid core and the dog 33 is moved into engagement with the surface of the same to enter the notch 35 75 when by longitudinal movement of the core it is brought in register therewith.

The withdrawal of the dog 32 from the respective notch in the core, releases the blocking mechanism of the track appliance 80 and thereby permits the normally compressed springs 15 to impel the stops outwardly through the slots in the wall of the base and into the corresponding slots of the rail, thereby placing the track appliance in 85 an operative condition by blocking the downward movement of the rail as hereinbefore explained.

90 The longitudinal movement of the solenoid core by action of the springs 15 is terminated when the dog 33 which was held in frictional contact with its surface by the spring 38, enters the notch 35 and the parts thus remain in their adjusted position until the line circuit is again closed to return the 95 semaphore to a position of "safety". When this occurs, the relay is again energized and moves its armature into engagement with the contact pieces 52 and 58, thereby closing the circuits of the solenoid and the electro- 100 magnet 30.

95 Inasmuch as during movement of the core by the springs 15 of the track appliance, the spreader 78 was removed from its position between the contact blades 29, the solenoid circuit is closed at that point with the result that when the circuit is subsequently closed in the relay, the solenoid is energized. The magnet 30 being likewise energized by the closing of its circuit in the relay, moves 110 the dog 33 out of the notch it occupied leaving the core of the now active solenoid free to be attracted to its original position until its movement is arrested by the dog 32 entering the notch 34 and a synchronous opening of the solenoid circuit when the spreader 115 separates the contact blades.

120 The inward movement of the core of the solenoid effected by the flow of current through the coil of the same, withdraws the stops from the openings in the rail and recompresses the springs 15 in which condition the parts are locked by the magnet 30 as soon as the dog 32 has entered the respective notch in the core.

125 In the diagram shown in Fig. 10, a series of track appliances 60 are by the above described method, operatively connected in the line circuit through the medium of one relay which controls the flow of current through 130

two circuits in which all the solenoids and all the electro-magnets of the track appliances are connected.

The series of track appliances are provided to co-operatively actuate a movement-controlling mechanism of the type shown and described in my application for patent No. 40,898, filed synchronously with the present one. They are placed at substantially 10 equal distances apart ahead of one of the semaphores 61 of the signaling system with relation to the direction in which trains or other vehicles equipped with the movement controlling mechanism travel along the railroad, and the relay is connected in the line 15 circuit of the signaling system at a point between its source and the point of its connection with the semaphore so that even though the connections of the semaphore in the line circuit are broken, or the operating 20 mechanism of the semaphore is in an inoperative condition, the relay will be deenergized when the normally closed line circuit is opened.

25 The detonator signaling apparatus used in connection with the track appliance comprises an endless band composed of a pair of sprocket chains 62 which are mounted upon wheels 63 rotatably supported in bearings 64 erected upon the exterior flange of 30 the base of the track appliance.

The chains are at equidistant points, connected by detonators 65 of the type commonly used on railroads.

35 One of the stops 10 of the blocking mechanism of the track appliance is connected to the bar 16 of the same by means of a flexible shank 66 which permits of its up and downward deflection.

40 The band on which the detonators are carried is mounted in a position with relation to the trip-rail so that its upper portion moves between the resilient stop in its projected position and an anvil 67 installed adjacent the track instrument in vertical alignment with the stop.

45 The detonators on the band are fed into the space between the stop and the anvil by a gravity pawl 68 which engages the teeth 50 of a ratchet wheel 69 mounted upon the shaft of one of the sets of sprocket wheels upon which the chains 62 are supported.

The rail of the track appliance in an effective condition has sufficient play to permit of a limited downward movement by 55 which the pawl is advanced along the toothed periphery of the ratchet wheel. When subsequent to a limited downward movement of the rail, it is returned to its 60 original position by the expansion of the springs 4, the pawl interlocking with a tooth of the ratchet wheel rotates the therewith connected sprocket wheel through a determinate angle and thereby advances the chain 65 in the direction of the arrow A in Fig. 5.

During downward movement of the rail when the blocking mechanism is in its operative condition, the stop 10 which is connected with the bar 16 by the resilient shank 66, is compelled to forcibly engage the detonator disposed above the anvil and thereby explodes the same. 70

To prevent the feed movement of the detonator-band during the extended downward movement of the rail when the track appliance is in its ineffective condition, the pawl 68 is provided with a wrist 70 which extends into a slot of a cam 71 attached to the adjacent standard 64 upon which the sprocket wheels of the detonator apparatus 80 are rotatably supported.

The cam-slot is pear-shaped and has at its upper and lower ends, leaf-springs 72 which prevent return movement of the wrist past the points at which they are located. 85 When by downward movement of the rail the wrist is moved past the spring at the lower end of the cam-slot it is compelled to travel during return movement of the rail, through the opposite side of the slot and thus moves free from engagement with the ratchet wheel until after it has passed the spring at the upper end of the slot, it reassumes by gravity its original position. 90

It will be observed that to project the resilient stop beyond the outer surface of the rail a distance sufficient to cause it to engage the detonator during downward movement of the same, it is necessary that while the blocking mechanism is in its inoperative condition, the stop extends partially into the 95 respective slot of the rail. 100

The flexible shank which connects the stop with the bar 16 permits it to deflect during downward motion of the rail and thereby 105 prevent its obstructing the movement of the same.

It will be seen that the stops 10 when the blocking mechanism is in its operative condition, not only obstruct the downward 110 movement of the trip rail, but also lock the same against upward displacement by their position within the slots 14.

While I have shown and described the co-operative mechanical and electrical devices 115 comprised in my invention in the best and simplest form at present known to me, I desire it understood that variations in the construction, form and arrangement of the parts may be resorted to within the spirit 120 of my invention as defined in the appended claims:

1. A track appliance of the character described comprising a base, a trip-rail yieldably mounted thereon, spring-operated 125 means for blocking the movement of the rail, a device for retracting said means to an inoperative position, and a device co-operative with the first-mentioned device to hold the said means in the retracted position. 130

2. A track appliance of the character described comprising a base, a trip-rail yieldably mounted thereon, spring-operated means for blocking the movement of the rail, an electric device for retracting said means to an inoperative position, and an electric device co-operative with the first-mentioned device to hold the said means in the retracted position. 70
- 10 3. A track appliance of the character described comprising a base, a trip rail yieldably mounted thereon, spring-operated means for blocking the movement of the rail, a circuit, a solenoid for retracting the said means to an inoperative position, in said circuit, a second circuit, an electro-magnetic device for locking the core of the solenoid in a determinate position, in said second circuit, a third circuit and a relay in said third circuit, controlling the circuits of the solenoid and the said electro-magnetic device. 75
- 15 4. A track appliance of the character described comprising a base, a trip-rail yieldably mounted thereon, spring-operated means for blocking the movement of the rail, a circuit, a solenoid for retracting the said means to an inoperative position, in said circuit, a second circuit, an electro-magnetic device for locking the core of the solenoid in a determinate position, in said second circuit, a relay controlling the circuits of the solenoid and the said electro-magnetic device. 80
- 20 5. A track appliance of the character described comprising a base, a trip-rail yieldably mounted thereon, spring-operated means for blocking the movement of the rail, a circuit including a solenoid for retracting the said means to an inoperative position, a second circuit, an electro-magnetic device for locking the solenoid core in a determinate position, in said second circuit, a relay adapted to close breaks in the circuits of the solenoid and the magnet, and a circuit breaker operated by action of the solenoid core. 85
- 25 6. A track appliance of the character described comprising a hollow base, a trip-rail yieldably mounted on said base, spring-actuated mechanism for blocking the movement of the rail, including a pair of levers fulcrumed in the base, stops operatively connected with said levers to be moved synchronously to points in the path of said rail, springs for effecting the said movement of the stops, and means connected with said levers for holding them in a position in which the stops are in a retracted position. 90
- 30 7. A track appliance of the character described comprising a hollow base, a trip-rail yieldably mounted thereon, mechanism within the base for blocking the movement of the rail, means for effecting a water-tight connection between the base and the rail, devices controlling the operation of said mechanism, and a casing inclosing said devices, in water-tight connection with the base. 95
- 35 8. A track appliance of the character described comprising a hollow base-member, a rail-member yieldably mounted thereon, mechanism within the base-member for blocking the movement of the rail-member, and a strip of resilient metal connected with one of said members in frictional contact with the other member, for effecting a watertight connection between the members. 100
- 40 9. The combination with a track-appliance of the character described, including a trip member to effect an operative movement of an element brought in contact therewith, of a detonator signal apparatus associated with said trip-member to operate synchronously therewith. 105
- 45 10. The combination with a track-appliance of the character described, including a trip-member to effect an operative movement of an element brought in contact therewith, of a detonator signal apparatus associated with said trip member to operate synchronously therewith, and including a series of detonators, and means for feeding said detonators to an operative position by action of said member. 110
- 50 11. A track-element of the character described comprising a base, a rail yieldably mounted thereon, an anvil, mechanism for limiting the movement of the rail, including a projectable part, and a detonator signal appliance for interposing a detonator between the said part and the said anvil. 115
- 55 12. A track element of the character described comprising a base, a rail yieldably mounted thereon, an anvil, mechanism for limiting the movement of the rail, including a projectable part, a detonator-signal apparatus carrying a series of detonators, and co-operative means on the rail and the said appliance for feeding the said detonators to an operative position between the said part and the said anvil. 120
- 60 13. A track element of the character described comprising a base, a rail yieldably mounted thereon, an anvil, mechanism for limiting the movement of the rail, including a projectable part, a detonator signal-apparatus carrying a series of detonators, co-operative means on the rail and the said appliance for feeding the said detonators to an operative position between the said part and the said anvil, and a device for rendering said means inoperative during a yielding movement of the rail while the said mechanism is in an inoperative condition. 125
- 65 14. A track element of the character described, comprising a base, a rail yieldably mounted thereon, an anvil, mechanism for limiting the movement of the rail, including 130

- a projectable part, a detonator signal apparatus comprising a movably mounted endless belt carrying equidistant detonators and passing between the said part and the said anvil when the said part is in its projected position, a ratchet-wheel in driving connection with said belt, and a pawl on the rail in operative engagement with said sprocket wheel.
- 10 15. A track element of the character described, comprising a base, a rail yieldably mounted thereon, an anvil, mechanism for limiting the movement of the rail, including a projectable part, a detonator signal apparatus comprising a movably mounted endless belt carrying equidistant detonators and passing between the said part and the said anvil when the said part is in its projected position, a ratchet wheel in driving connection with said belt, a pawl on the rail in operative engagement with said sprocket wheel, and means for separating the pawl from the sprocket wheel during yielding movement of the rail while the said mechanism is in an inoperative condition.
- 15 20. The combination with the line circuit of a railway block signaling system, of a track appliance including mechanism for placing it in an operative condition, an electric device controlling said mechanism, and a relay controlling the circuit of said device and connected in the line circuit.
- 25 30. The combination with the line circuit of a railway block signaling system, of a track appliance including mechanism for placing it in an operative condition, an electric device controlling said mechanism and a relay controlling the circuit of said device and connected in the line circuit.
- 35 40. 18. The combination with the line circuit of a railway block-signaling system, of a series of track appliances each including mechanism for placing them in an operative condition and an electric device controlling

said mechanism, and a relay controlling the 45 circuits of the said devices and connected in the line circuit.

19. A track appliance of the character described comprising a base including an upwardly extending wall and a trip-rail yieldably mounted on said base and having a recess to admit said wall.

20. In combination, a yieldably held trip, an appliance adapted to block yielding movement thereof, normally active means to 55 impel said appliance to its blocking position, a circuit, an electric apparatus connected therein and adapted to move said appliance to an inoperative position against the action of its said impellent means, said 60 apparatus including a device for locking the appliance in its said inoperative condition, and a circuit-breaker interrupting the circuit while the appliance is in its inoperative condition and closing the same by its 65 movement to its operative position when released.

21. In combination, a yieldably held trip, an appliance adapted to block yielding movement thereof, normally active means 70 to impel said appliance to its blocking position, a circuit, an electric apparatus connected therein and adapted to move said appliance to an inoperative position against the action of its said impellent means, said 75 apparatus including an electrical device for locking the appliance in its said inoperative condition, and a circuit-breaker interrupting the circuit while the appliance is in its inoperative condition and closing the same 80 by its movement to its operative position when released.

In testimony whereof I have affixed my signature in presence of two witnesses.

JAMES CULTON.
